UNITED STATES PATENT OFFICE.

RICHARD SLEE, OF SWIFTWATER, PENNSYLVANIA.

CONTAINER APPLICATOR.

1,415,413.

Specification of Letters Patent. Patented May 9, 1922.

Application filed March 29, 1921. Serial No. 456,621.

To all whom it may concern:

Be it known that I, RICHARD SLEE, a citizen of the United States, residing at Swiftwater, in the county of Monroe, and State 5 of Pennsylvania, have invented certain new and useful Improvements in Container Applicators, of which the following is a specification.

This invention relates to container-applicators and has for an object to provide a device of the class embodying new and improved features both as a container and as 10 an applicator. A further object of the invention is to provide a container having a 15 plunger, or follower, moving therein to expel the contents, with improved means for actuating the plunger.

A further object of the invention is to provide a container having a plunger, or 20 follower, of improved type movable therein, with a manually rotatable screw for feeding the plunger.

A further object of the invention is to provide improved means for connecting the 25 plunger-operating screw with the container.

A further object of the invention is to provide a new and improved type of applicator with improved means for attaching the same to the container.

With these and other objects in view, the 30 invention comprises the novel units, elements, parts, combinations, mechanical movements and functions disclosed in the drawings, together with equivalents thereof, 35 as hereinafter more fully described and claimed.

In the drawings—

Figure 1 is a view of the improved container-applicator in side elevation.

Fig. 2 is a longitudinal diametrical sectional view through the container.

Fig. 3 is a transverse sectional view 40 through the container and plunger, as indicated by the line 3—3 of Fig. 2.

Fig. 4 is a transverse sectional view 45 through the cap, as indicated by line 4—4 of Fig. 2.

Fig. 5 is a detailed perspective view of 50 the several interior operating parts, removed from the container and separated.

Fig. 6 is a detailed perspective view of the 55 several parts of the container, applicator and cap, disconnected.

Like characters of reference indicate corresponding parts throughout the several 55 views.

The improved container-applicator, which forms the subject matter of this application, comprises a container 10 preferably substantially cylindrical throughout the 60 greater portion of its length, having a neck 11 and bead 12. The neck 11 is also provided with a bead 13 forming an inclined annular shoulder 14 within the neck opening. This container in most cases will 65 preferably be composed of glass and has been shown section-lined to indicate glass at Fig. 2, but it is to be understood that such preferred material, or such section lining indicating such material, is no limitation 70 upon the present invention and the container may be made of any desired or approved material.

To operate in conjunction with the container a screw 15 is employed, preferably 75 originally constructed as a straight rod cross-sawed at 16 as indicated in Fig. 3. A knurled head 17 is rigidly secured to the screw 15 after the plunger has been applied thereto. The plunger comprises a nut 18 80 having piercing points 19 inserted into the washer 20 forming a part of the plunger. The washer 20 will preferably be composed 85 of cork, although the invention is not limited to such material. The axial opening 21 through the washer 20 will be of greater diameter than the screw 15 so that when applied to the nut 18 will be free from engagement with the screw 15 as shown more particularly at Fig. 2. 90

The screw 15 with the knurled head 17 and plunger, will be inserted into the container 10 with the sawed extremity disposed within the annular tapered shoulder 14. The extremity is now expanded, by inserting 95 an instrument into the saw kerfs, so that the expanded extremities will engage against the inclined shoulder 14 as indicated at 22 in Fig. 2, or the head will be first expanded and the screw 15 inserted 100 before the knurled head is applied, the screw being held against rotation within the container by any convenient tool and the knurled head 17 applied thereto.

The container 10 will be filled with the 105 material as indicated at Fig. 2. The filling

may be accomplished either before the plunger 20 is inserted or after the plunger is inserted and filled through the saw kerfs 16 in the expanded extremity of the screw 15. 5 The manner and time of filling will depend upon the nature of the material filled into the container.

After the container is filled, a washer 23 will be applied to the end of the neck 11 and 10 preferably secured thereon by some adhesive material, impervious to and insoluble in, the contents of the container. This washer 22 is preferably composed of cork and is of reduced thickness centrally as indicated at 15 24 in Fig. 2. The application of this washer to the container by the impervious adhesive will completely close the container against evaporation or discharge of the contents.

An applicator is now applied to the structure, such applicator being shown as an entirety at 25. It comprises a cylindrical portion 26 properly proportioned to embrace the bead 13 of the neck and a tapered portion 27 having a discharge orifice 28. For the 25 purpose of proper sealing, the cylindrical part is preferably coated with the said impervious adhesive and applied to cover the washer 23 and the bead 13, and the marginal edge 29 is burnished down to engage against the underside of the bead 13 as indicated 30 more particularly at Figures 1 and 2. If the contents of the container is liquid and volatile, a fibrous packing 30 will preferably be enclosed within the applicator as indicated at Fig. 2. A closure cap 31 is provided to close the discharge orifice 28 when not required for use.

With the parts assembled and filled, as indicated at Fig. 2, the contents are made 40 available by inserting an instrument, such as a needle or pin, through the orifice 28 passing through the fibrous packing 30, if therein contained, and piercing the reduced portion 24 of the washer 23. Manual rotation of the 45 screw 15 by power applied to the knurled head 17 will cause the plunger to move along within the cylinder to expel the contents through the puncture of the washer 23 to saturate the fibrous packing 30 and be extended through the orifice 28.

It has been found from experiment that, with the washer 20 of the plunger in engagement with the interior of the cylinder but out of engagement with the screw, while 55 the nut 18 is in engagement with the screw but out of engagement with the container, the turning of the screw will not materially rotate the plunger but will move it substantially only longitudinally to expel the contents.

It is obvious that the fibrous packing will be desirable only when the contents is liquid and when the contents is plastic or semi-liquid can and will be omitted. It is also 65 obvious that if the container is employed

for a material sufficiently plastic the washer 23 may also be omitted, depending upon the cap 31 for sufficient closure of the container.

In any event, after the extrusion of the material from the orifice 28 and the application thereof by the tapered applicator 27 or otherwise as may be found advantageous, the cap 31 will be replaced to close the orifice 28 and protect the applicator. 70

The present invention is intended for a 75 container and applicator for highly volatile liquid medicinal preparations and, in its entirety in organized form, is capable of serving such purpose. It is, however, not limited thereby or thereto. 80

I claim—

1. A container-applicator comprising a body having an inclined annular shoulder at one end, a screw inserted through the body and having its extremity expanded to 85 form means for engaging the shoulder and passages for the contents, a plunger mounted to move within the body and means to apply manual stress to apply the action of the screw to the plunger. 90

2. A container-applicator comprising a body having a tapered annular shoulder, a screw inserted longitudinally through the body and having its extremity expanded to 95 form a member bearing against the shoulder and passages for the contents therebetween, a plunger within the container upon and adapted to be actuated by the screw, and means attached to the screw for applying manual stress thereto. 100

3. A container-applicator comprising a cylindrical body, a plunger mounted within the body comprising a yielding disc and a non-yielding nut, the said disc being in perimetrical frictional engagement with the 105 container, a screw inserted through the disc and nut being out of engagement with the disc, and means to manually rotate the screw to move the plunger.

4. A container-applicator comprising a 110 substantially cylindrical body, a plunger mounted within the body comprising a yielding disc and a non-yielding nut, the disc being provided with an opening of greater diameter than and concentric therewith the 115 opening of the nut and in perimetrical frictional engagement with the interior of the container, and a feed screw loosely inserted through the opening of the disc and through the nut. 120

5. A container-applicator comprising a body having a constricted neck and bead, an applicator member embracing the bead and having a margin burnished under said bead, a plunger within the body and means to advance the plunger to discharge material through the applicator. 125

6. The combination with a substantially cylindrical container having a reduced neck and enlarged bead of an applicator embrac- 130

- ing the bead and having its margin burnished under and rigidly engaging said bead, a screw extending axially of the cylindrical container and having an extremity forming an orificed bearing upon the neck, a plunger operating upon the screw adapted to move longitudinally within the container, and means externally of the container for applying manual stress to the screw.
- 10 7. The combination with a substantially cylindrical container having a reduced neck and enlarged extreme bead forming a tapered annular shoulder at the extremity of the neck of an applicator embracing the 15 bead and having its margin burnished beneath the bead to form a rigid engagement therewith, a screw extending axially through the container and having its extremity expanded into a bearing upon the tapered shoulder forming discharge orifices, a plunger mounted within the container having a yielding part in frictional engagement with the container and out of engagement with the screw and a non-yielding part in engagement with the screw and out of engagement 20 with the container and means externally of the container for applying manual stress to rotate the screw.
- 10 7. The combination with a substantially cylindrical container having a reduced neck and enlarged extreme bead forming a tapered annular shoulder at the extremity of the neck of an applicator embracing the 15 bead and having its margin burnished beneath the bead to form a rigid engagement therewith, a screw extending axially through the container and having its extremity expanded into a bearing upon the tapered shoulder forming discharge orifices, a plunger mounted within the container having a yielding part in frictional engagement with the container and out of engagement with the screw and a non-yielding part in engagement with the screw and out of engagement 25 with the container and means externally of the container for applying manual stress to rotate the screw.

In testimony whereof I affix my signature.
RICHARD SLEE.
